METAL DEGASSING APPARATUS

Charles W. Finkl, Chicago, Ill., assignor to A. Finkl & Sons Co., Chicago, Ill., a corporation of Illinois
Filed July 22, 1965, Ser. No. 477,083
8 Claims. (Cl. 266—39)

This application is a continuation-in-part application of copending application Serial Number 108,513, filed May 8, 1961, now abandoned.

My invention relates to degassing molten metals. It relates particularly to apparatus which will enable the included gas content in a heat of molten metal to be reduced to very low levels within the permissible temperature drop limitation of the metal. The apparatus enables reduction of the included gas content to be accomplished by the use of vacuum as the sole degassing agent.

In recent years there has been an increasing demand for higher and higher quality in all types of steel. Increased ductility, toughness, and transverse properties have become of particular importance. My invention enables increased ductility, toughness, and transverse properties to be achieved with little, if any, increase in the cost of production.

It is believed that ductility and toughness are related in some degree to the included gas content of the metal, particularly hydrogen and oxygen. A large included hydrogen content, for example, results in flaking. A high oxygen content indicates high oxide inclusions. At the present time it is thought that flaking, or the presence of cracks, can be reduced by heat treatment after the metal has been poured. Heat treatment is effective to reduce cracking, but heat treatment does not have much effect on ductility.

A second method of increasing ductility and toughness is to degas the molten metal. It is believed that heat treatment can be curtailed when degassing is employed and it is therefore possible that the overall cost of producing the steel will be reduced.

The above comments are particularly pertinent to the production of steel in large quantities. Other problems equally serious face the foundry man who pours castings from heats on the order of from 1 to 10 tons. In castings poured from heats of this size, hot tearing is very much a problem if the included gas content is high. In addition, it is very desirable to reduce the "dirt" in castings. By the term "dirt" I mean oxides or inclusions which result from the presence of too much hydrogen, nitrogen, and, particularly, oxygen in the metal.

Various methods of treating the molten metal before it is poured into molds have been proposed. Many of them are impractical due to the special equipment needed which is not practical for day in, day out production. Other methods require the molten metal to be treated for such a length of time between tapping and pouring that the permissible temperature drop limitation of the metal is exceeded.

Permissible temperature drop limitation as used in this specification and claims relates to that drop in temperature which can be tolerated before the metal is considered too cold for pouring. If a heat of low alloy steel is tapped at approximately 3,100 degrees F., the permissible temperature drop limitation expressed in terms of temperature would be on the order of 250 degrees F., depending to some extent on the composition of the steel and other factors. Permissible temperature drop limitation may also be expressed in terms of time. When so expressed, it may be considered to be that length of time elapsing between the time the steel is tapped until it is so cold as to be unsuitable for teeming.

Accordingly, a primary object of this invention is to

2

provide means for degassing small heats of molten metal which will reduce dirt and the tendency to hot tear, and provide increased ductility, toughness, and transverse strength in the final product, particularly castings.

Another object is to provide an apparatus for achieving the above objects utilizing vacuum as the sole degassing agent which will enable the metal to be degassed within its permissible temperature drop limitation.

Another object is to provide a new and improved ladle for degassing small heats of molten metal.

Another object is to provide a vacuum degassing assembly which includes a ladle assembly and a unique hood covering the upper surface of the melt to thereby reradiate heat back to the melt, or, in other words, conserve the heat of the steel in the ladle assembly.

Other objects and advantages will become apparent from a study of the following specification and claims.

My invention is illustrated more or less diagrammatically in the accompanying figures wherein:

FIGURE 1 is a side elevation with portions broken away;

FIGURE 2 is a front elevation taken substantially along the line 2—2 of FIGURE 1;

FIGURE 3 is a top view taken substantially along the line 3—3 of FIGURE 1 with portions omitted for clarity; and

FIGURE 4 is a side view of my degassing unit positioned within a vacuum tank.

Like reference numerals will be used to refer to like parts throughout the following description of the drawings.

In FIGURE 1 my degassing assembly is indicated generally at 10. It includes a lower portion which is essentially a ladle 11 and an upper portion 12 which acts as a radiation shield and enables almost the full depth of the ladle to be utilized as explained hereinafter. As can be seen in any one of FIGURES 1, 2 and 4, the degassing unit is essentially barrel shaped. A stopper rod is indicated generally at 13 and a stopper rod rigging at 14. In this instance a bottom ladle has been illustrated but the invention is not limited to this type of ladle. A lip pour or teapot ladle could also be used.

The wall of ladle 11 consists essentially of an outer steel shell 15 and an inner lining 16 of refractory may be used and the thickness may vary anywhere from 4 to 5 inches, or perhaps more or less, depending to some extent on the size of the ladle and the requirements at a given installation. A bottom plate 17 is welded about its periphery to the lower edge of steel shell 15. A skirt 18 is welded to plate 17 to form a support for the degassing unit.

The walls of the lower portion diverge slightly outwardly in an upward direction as can best be seen in FIGURES 1, 2 and 4. A plurality of radially outwardly directed U-shaped lugs 20, 21, 22 and 23 are welded to the steel shell 15 at the point of maximum circumference. The upper surfaces of the lugs are coplanar with the upper surface of the walls, and the lugs are equally spaced one from another.

A band 25 is secured to the exterior of the ladle. A pair of trunnion plates 26, 27 are bolted to the band 25. Each trunnion plate includes a trunnion journal 28, 29 which receives a trunnion 30, 31, respectively.

The upper portion 12 of the degassing unit has the shape of a lopsided frustum of a cone. The wall construction of the upper section is structurally similar to the ladle portion in that it consists of an outer shell 33 to which a suitable layer of refractory, not shown, is secured. The upper section terminates at its upper end in a flange 34 and at its lower end in a connecting flange 35. Slots 36 in flange 35 overlie the slots in lugs 20—23.

Suitable connecting bolts, not shown, secure flange 35 to lugs 20-23 to thereby connect the upper and lower sections.

The slope of the walls of upper section 12 varies from a maximum at 38 to a minimum in the wall section area designated generally at 39.

The provision of a sloped wall surface is especially advantageous in reducing refractory drip. It appears that the inclined surface retains or absorbs less heat than does a flat surface and consequently the illustrated configuration is more advantageous than a flat disc located at the level of flange 35. The radiation shield or skirt 12 is therefore an important feature in the conservation of heat during the degassing process. The provision of a relatively flat refractory surface at an elevation considerably above the level of flange 35, such as closure member 64, is acceptable since the intensity of the radiant heat varies with the square of the distance from the source and accordingly the problem of refractory drip is not so acute at the higher elevation.

The provision of a sloped or upwardly and inwardly extending wall surface in the region next adjacent the top of the ladle is also of great advantage from the standpoint of ladle maintenance. Since the level of the molten metal may be very close to the top of the ladle some metal may be deposited on the upwardly and inwardly extending surface. The sloped surface makes stripping of the deposited metal a relatively simple task as compared to refurbishing a flat surface.

A tapping opening 40 is cut in the area of minimum slope. By locating the tapping opening 40 in the wall section of minimum slope, a tapping opening of maximum horizontal area is provided for a given area of opening.

A removable door is indicated generally at 42. The door consists essentially of a flat plate 43, a depending sheet 44 which is contoured to make snug engagement with the wall section 39, and a suitable layer of refractory 45. An inverted U-shaped frame 46 is pivoted about a rod 47 which in turn is journaled in a pair of pivot plates 48, 49 welded to flange 35. Frame 46 carries a pivot rod 50 which is received in a pair of plates 51, 52 projecting outwardly from plate 43. In order to prevent the door from revolving about pivot rod 50 when it is swung clockwise to permit molten metal to be poured into the ladle, a stop 53 is welded to the upper end of the door supporting frame 46. A stop bar 53a welded to the outer lower edge of pivot plates 48, 49 prevents the frame 46 from swinging downward against the ladle.

The black head 54 of stopper rod 13 seats in a discharge nozzle 55 located in a pouring opening in the bottom of the ladle. Any suitable means may be provided for securing the nozzle to the ladle. In this instance, a plate 56 has been bolted to a ring 57 welded to the bottom plate 17. The plate 56 bears against a shoulder in nozzle 55.

The stopper rod rigging 14 may be of any conventional design. As can be observed from FIGURE 1, a conventional tipping rigging has been modified to the extent that the rod may only be moved up and down. In other words, by rotating handle 58 vertical rod 59 is raised and lowered. Supporting arm 60 is bolted to rod 59 at its inner end and threadably connected to stopper core rod 61 at its outer end. Rotation of handle 58 thereby seats and unseats the nozzle.

The upper end of the section 12 is apertured as at 63 to permit entry of the stopper rod 13. The stopper rod carries a radiation plate 64 which consists essentially of a flat circular plate 65, a depending skirt 66 welded thereto, and a layer of refractory material 67 secured to plate 65. As can best be seen in FIGURE 1, radiation plate 64 substantially overlaps opening 63. It is spaced a few inches away from the opening to thereby provide a gas escape passage 68 for gases given off by the molten metal in the ladle 11.

The use and operation of my invention are as follows:

In order to degas a heat of molten metal, a stopper rod 13 is first seated on the nozzle 55. Door 42 is then swung open and the degassing unit positioned to receive metal from a furnace or other source of supply. Molten metal is then admitted to the degassing unit. At A, B and C I have indicated molten metal levels for 2, 2½, and 3½ tons of steel.

After the desired amount of steel is tapped into the ladle, door 42 is swung shut. With door 42 and radiation plate 64 in place, the upper section 12 forms, in effect, a substantially continuous radiation shield over the surface of the exposed metal. Since a substantially continuous hood or shell of refractory is provided, heat loss from the upper surface of the metal is kept at a minimum. It is desirable that radiation plate 64 overlap the opening 63 in order to prevent any radiant heat from passing unobstructedly out of the ladle.

The degassing unit is then placed in the vacuum chamber indicated generally at 70 in FIGURE 4. It will be understood that the degassing unit will be transferred by bail 71 which is locked in the position shown in FIGURES 2 and 4 by handle 72. The inner end of handle 72 is received in a slot formed in dog 73 welded to flange 35. The vacuum tank is large enough to clear the bail 71. The tank is shown in closed position by dotted lines 74 in FIGURE 4. In this instance, a clam shell type vacuum tank has been illustrated. Essentially the tank consists of a stationary half 75 and a movable half 76 which swings about pivot 77. A cylinder and piston arrangement 78, 79 operated by hydraulic fluid from a source, not shown, opens and closes the tank. A vacuum is drawn through conduit 80. The degassing operation can be observed through the window 81. The two halves of the clam shell tank carry sealing flanges 82, 83 which, when in engagement, form an air-tight seal which enables a vacuum on the order of 1 millimeter of mercury or less to be drawn in the tank.

At the conclusion of the degassing operation, the tank is opened. If a large number of small castings are to be poured, a synthetic or inert slag may be added to the degassed melt in order to conserve heat between the end of the degassing operation and the end of the pouring operation. By inert or synthetic slag, I mean a slag which will not give off to the heat deleterious gases similar to those drawn off by the degassing operation. My apparatus therefore enables the melt to be degassed without a slag blanket. The presence of a slag blanket during degassing would lengthen the degassing cycle and hinder the degassing. As a result, stratification of the metal may occur.

The unique construction of the upper section or radiation shield is especially important to the excellent results obtainable from my degassing unit.

In the first place, the radiation shield, which might be described as a heat conservation shield, reduces temperature drop to an absolute minimum. This provides maximum opportunity for removal of deleterious gases since the slow drop in temperature enables the molten metal to be subjected to a vacuum for the longest possible time before the permissible temperature drop limitation is reached. Part of the heat loss from the metal takes the form of heat transfer through the hood. If a metal shield were used, it would become red hot in use, and since it would always be at a temperature considerably below that of the molten metal, a large temperature differential would exist and loss by heat transfer would be excessive. By lining the outer metal shell 33 with refractory, the temperature differential between the metal and hood is reduced to zero, or close to it, since the refractory will heat to, or close to, the temperature of the molten metal.

In addition, the refractory protects the metal shell 33 from the heat of the melt.

In the second place, the heat conservation shield is as small bulkwise, i.e., volume, as it can be. Therefore,

the amount of heat lost due to absorption by the shield is at a minimum. It will be noted that upper section 12 at its widest point is only as wide as the upper end of the ladle 11. The inwardly, roughly parabolic-shaped contour is the smallest bulk of material that can be utilized consistent with providing boil clearance. Loss by heat absorption accounts for much of the heat lost otherwise than by transference through the hood.

In the third place, the heat shield enables the ladle 11 to be filled to a higher level than any comparable ladle I am aware of that is used in vacuum degassing. Note, for example, line C in FIGURE 1. Without the heat shield, the ladle could only be filled to approximately the A level, or perhaps even below. This is because the boil in the ladle created by the vacuum throws metal up approximately two feet above the surface in a ladle similar to that shown in the drawings. Without the heat shield, the boil would throw metal out of the ladle if the molten metal level is at C. With the heat shield, the ladle can readily be filled to level C since the boiling metal will splash against the refractory, which is at substantially the same temperature as the steel, and fall back into the ladle. A flat shield could not be used of course as it would provide no clearance for the carbon monoxide boil.

This increased capacity of the ladle is of particular importance to the small foundry man who pours a wide range of sizes of castings. With a 3½ ton ladle, for example, he may be able to pour 3 to 3¼ tons of metal so that two 1½ ton castings could be poured in one heat. Without the hood, only 2 to 2½ tons of metal could be handled, and thus only one 1½ ton casting could be poured per heat. The heat conservation shield therefore, in effect, doubles the foundry man's capacity.

Actual final included gas contents of 1.1 p.p.m. H₂, 23 p.p.m. N₂, and 25 p.p.m. O₂ have been achieved in approximately 5,000 pound heats tapped at around 3,120 degrees F. and degassed for approximately 5 minutes. Total elapsed time from start tap to teem has varied from 14 to 23 minutes. Total elapsed times of 14 to 16 minutes have been consistently achieved. The aforementioned times are well within the permissible temperature drop limitation of the steel degassed. The steel had a nominal composition of C .50-.60, Mn .65-.90, Si .20-.35, Ni .80-1.00, Cr .80-1.10, Mo .25-.35.

Although a preferred embodiment has been illustrated and described, it will be understood that the invention is not so limited in application. Accordingly, the scope of the invention should only be limited by the scope of the hereinafter appended claims.

I claim:

1. A degassing unit for lowering the included gas content in commercial sized baths of molten steel within the permissible temperature drop limitation of the steel, said degassing unit including a ladle and a radiation shield assembly carried by and overlapping the ladle to thereby form a substantially uninterrupted heat radiating surface over the ladle, the interior lining of the shield being composed of a refractory material, said radiation shield assembly having walls which converge upwardly, inwardly from the upper end of the ladle to thereby provide a radiation shield for conserving the heat of the steel in the ladle, said walls converging upwardly, inwardly non-uniformly to thereby provide a wall section of minimum slope as contrasted to the balance of the wall, said wall section of minimum slope having a tapping opening therein whereby molten steel may be admitted to the ladle, a cover for the tapping opening pivoted on the degassing unit, said cover, when in position covering the tapping opening, forming a portion of the substantially continuous heat radiating surface, a stopper rod carried by radiation shield assembly, and a radiation plate carried by and removable with the stopper rod, said radiation plate overlying an opening in the radiation shield through which the stopper rod passes and being out of contact therewith at all times

to thereby provide a gas escape passage for gases given off from the molten steel in the ladle, said radiation plate forming a portion of the substantially continuous heat radiating surface.

5 2. The degassing unit of claim 1 further characterized in that the radiation shield assembly, at its widest point, is substantially co-terminous with the upper end of the ladle and is in operative contact with the upper end of the ladle whereby the heat storage capacity of the radiation shield assembly is at a minimum.

10 3. An apparatus for lowering the included gas content in commercial sized baths of molten metal within the permissible temperature drop limitation of the metal, said apparatus including a receptacle having structure defining 15 a gas escape passage therein discharging externally of the receptacle wall for the exit of gases removed from a bath of molten metal contained within the receptacle, said structure comprising a radiation assembly externally spaced from and peripherally overlapping the gas escape 20 passage, the upper portion of said receptacle converging inwardly, upwardly from a point in the vicinity of the highest molten metal level to thereby provide a reflecting shield for conserving the heat of the bath during tapping and treatment, one wall section of the upper portion of 25 said receptacle having a tapping opening therein for the reception of a removable tapping cover, which, when in position covering the opening, provides a substantially continuous radiation shield, said opening being of a size sufficient to provide easy access to the interior of the 30 receptacle to thereby facilitate filling thereof, and means for discharging degassed molten metal from the receptacle.

4. The vacuum degassing apparatus of claim 3 further characterized in that the upper portion of the receptacle converges inwardly non-uniformly to thereby provide a wall section of minimum slope, the tapping opening being located in said wall section of minimum slope to thereby provide maximum tapping access to the interior of the receptacle for a given opening area.

35 5. The vacuum degassing apparatus of claim 3 further characterized, firstly, in that the means for discharging molten metal from the receptacle includes a stopper rod seated in a discharge opening in the bottom of the receptacle, and, secondly, in that the radiation assembly 45 includes a radiation member, said stopper rod carrying the radiation member, said radiation member being spaced from an opening in the receptacle to thereby form the gas escape passage between the radiation member and the receptacle, said radiation member thereby forming a portion of the continuous radiation shield over the molten metal.

50 6. An apparatus for lowering the included gas content in commercial sized baths of molten metal within the permissible temperature drop limitation of the metal, said apparatus including a receptacle having structure defining 55 a gas escape passage therein discharging externally of the receptacle wall for the exit of gases removed from a bath of molten metal contained within the receptacle, and said structure comprising a radiation assembly externally spaced from and peripherally overlapping the gas escape 60 passage, the upper portion of said receptacle forming a shield for conserving the heat of the bath during tapping and treatment, one wall section of the upper portion of said receptacle having a tapping opening therein for the reception of a removable tapping cover, which, when in position covering the opening, provides a substantially continuous radiation shield, said opening being of a size sufficient to provide easy access to the interior of the receptacle to thereby facilitate filling thereof, and means for discharging degassed molten metal from the receptacle.

65 7. A radiant heat loss reduction assembly for use with a molten metal containing receptacle such as a vacuum degassing treatment receptacle, said assembly comprising 70 a generally upwardly and inwardly extending wall

75 a generally upwardly and inwardly extending wall

structure, the inclination of which commences substantially at the lower edge portion thereof,
said wall structure having a generally circular horizontal cross section at any vertical location,
the largest horizontal cross section occurring at the lower edge portion,
the smallest horizontal cross section occurring at the upper edge portion,
said upper edge portion terminating in an open outlet,
the periphery of which lies in a horizontal plane, and
an associated cover member overlying said upper edge portion,
said cover member being spaced above and out of contact with the said upper edge portion.

8. The radiant heat loss reduction assembly of claim 7 further characterized in that at least a portion of the central area of the cover member is substantially horizontal, said central area being located furthest away in a vertical direction from the lower edge portion of the wall structure.
